Specification for Design.

Patented Oct. 31, 1905.

Application filed September 22, 1905. Serial No. 279,726. Term of patent 3½ years.

To all whom it may concern:

Be it known that I, HELEN PARKER JOHN-
STONE, a citizen of the United States, residing
at Glenridge, in Essex county, State of New
Jersey, have invented a new, original, and or-
namental Design for Textile Fabrics, of which
the following is a specification, reference be-
ing had to the accompanying drawing, form-
ing a part thereof.

The figure is a plan view of the fabric, show-
ing my new design.

I claim—

The ornamental design for a textile fabric,
as shown.
